SYDNEY BORMAN, OF NEW YORK, N. Y., ASSIGNOR OF ONE-HALF TO LOUIS C. JANDORF,
OF PORT WASHINGTON, NEW YORK.

ILLUMINATING SIGN OR NUMBER-PLATE

1,169,117.

Specification of Letters Patent.

Patented Jan. 25, 1916.

Application filed December 29, 1914. Serial No. 879,462.

To all whom it may concern:

Be it known that I, SYDNEY BORMAN, a citizen of the United States, residing at the borough of Manhattan, in the city and county of New York and State of New York, have invented certain new and useful Improvements in Illuminating Signs or Number-Plates, of which the following is a specification.

10 My invention relates to signs, number plates, and the like adapted for illumination.

The objects of my invention are to provide a sign or plate adapted for illumination, 15 by either natural or artificial light; to render the faces of the same reversible; to insure a construction which will render the letters or figures distinct and the operation of the sign effective when the sign or the figures 20 and letters must occupy a small area; to reduce the number of parts to a minimum and thereby avoid rust generating in the joints, rattling, and insecurity; and to strengthen the structure, and to advantageously control direct rays.

Further objects are to produce signs or number plates in a cheap and effective manner whereby a minimum of material will be required, assemblage be dispensed with, 30 structural weakness be avoided, and speed of manufacture be insured.

To the above ends essentially my invention consists in such parts and combinations of parts as fall within the scope of the appended claims.

The invention will be described in connection with the specific embodiment shown, and the invention is not to be limited by such specific showing except for such limitations as the claims impart.

In the accompanying drawings, which are a part of this specification, and in which is shown an embodiment of the various features of my invention in the preferred form, 45 Figures 1, 2, and 3, are plan elevations of my novel plate in three phases or stages of its formation, Figs. 4, 5, and 6, central transverse sections of the same successively, Fig. 7, a rear elevation of the complete plate, 50 Fig. 8, a sectional view of my plate and an illuminating housing to which it is attached, and Figs. 9 and 10, front elevations of the plate on a reduced scale, showing the same in obverse and reverse respectively.

Like reference characters indicate like parts throughout the views.

In the construction illustrated a plate, sheet, or blank A of thin material such as metal, provided with marginal perforations a, if desired, for attaching or suspension means, has an intermediate portion B upwardly bent or pressed into a concavo convex form in cross section, as shown in Figs. 1 and 4; which portion in the present instance is intended to initially outline the numeral 1 or the letter I. It will be understood that the particular superficial form of the portion B in any instance is determined by the particular letter or numeral, or letters or numerals, that it is intended the plate shall ultimately bear.

The material of the plate A adjacent and surrounding the elevated portion B forms a flat marginal area b, which indicates the surface which is pierced or cut. In Figs. 2 and 5, where this phase of the process is shown, c indicates the line of piercing which is, however, interrupted by portions c', conveniently spaced from each other, which are not cut by the piercing means. The piercing operation is accompanied by a drawing operation. That is to say, as soon as the outline c is pierced the portions B and b are downwardly or rearwardly forced some distance out of the plane of the body of the plate A, as shown in Fig. 5, whereby at the points c' the material is drawn or elongated to form webs C, which, in the present instance, are six in number.

For a purpose to be later explained it is necessary that the perimeter of the portion b of the rear member be greater than the perimeter of the opening C' formed by the piercing operation on the line c. This is effected by forcing the arcuate portion B of the rear member into the plane of the marginal portions b. This operation results in increasing the superficial area of the rear member in all directions, as shown in Figs. 3 and 6, so that its edges are overlapped but out of contact with the body of the plate A leaving spaces d. Another result is that the webs C are forced into a slightly inclined position, which position they more readily assume because of their relative thinness due to the drawing operation. In its complete form, therefore, as shown in Figs. 3, 6, and 7, it comprises a

body A, provided with attaching perforations *a*, and with an opening or openings C' having the contour or contours of the letter or numeral or letters or numerals 5 which the sign is intended to indicate. A back plate or plates B having an outline or outlines corresponding with the outline or outlines C', but of greater perimeter is located in a plane behind the plate A, and 10 is connected thereto with webs C integral with the plates A and B between which webs are spaces *d*.

Display is rendered more effective by applying to the front surfaces of the plate 15 A and the plate B a black and a white coating of paint respectively, as at *e* and *e'*; and by applying to their respective back surfaces white and black coatings, as at *f* 20 and *f'*. Preferably the white surfaces are reflective, and the black surfaces dull or non-reflective.

This sign is adapted for reversal, and when employed in the dark with an artificial light in its rear and the black front face 25 exposed, the intensity of the light and reflection is increased by the white character of the back of the plate A and the front of the display plate B giving an effect such as shown in Fig. 9. By reversing the faces 30 of the sign under like conditions the display plate B in front of the plate A is shown in silhouette with the background, formed by the surface *f*, illuminated by reflection from the rear face of the member B, 35 as shown in Fig. 10. It is understood that many letters and numerals have a changed significance when reversed, and in such cases such reversal cannot be employed.

The larger area of the plate B relatively 40 to the opening in the body is required to cut off the direct rays of the illumination agent.

In Fig. 8 my sign is shown affixed to a casing G by means of screws *h* passing loosely 45 through the perforations *a*. In this casing is located an electric lamp J.

The sign may be manually reversed after removing the screws. When the sign is in-

tended for suspension, the suspending member may be passed through the perforations, and effectiveness may be enhanced by suspending before a window. The sign may, for some uses, merely rest upon its edge. 50

The described construction is such as lends itself to the display of letters of very 55 small dimensions located close together. The method of construction is inexpensive, and the structure itself by the use of the integral webs avoids the necessity of employing numerous attaching parts which result 60 in rust, derangement, and expense.

What I claim is:—

1. In a sign, a metal sign plate provided with an opening, a display plate adjacent the sign plate and spaced therefrom having 65 a contour similar to the contour of the opening but of greater dimensions than the opening, the sign plate being provided with reflective and non-reflective surfaces upon its opposite sides, the display plate being 70 provided with like surfaces upon its opposite sides, but reversely to surfaces of the sign plate, and spaced webs connecting the two plates.

2. In a sign the combination with a housing and a lamp in the housing, of a metal sign plate detachably mounted upon the housing adjacent the lamp, a display plate adjacent the sign plate and spaced therefrom having a contour similar to the contour of the opening but of greater dimensions than the opening, a white coating upon one side of the sign plate, a black coating on the other side of said plate, a white coating on one side of the display plate, and a black coating on the other side of the display plate, the coatings on each plate being arranged reversely to the coatings on the other plate, and spaced webs connecting the two plates. 75 80 85 90

In testimony whereof I have affixed my signature in presence of two witnesses.

SYDNEY BORMAN.
